UNITED STATES PATENT OFFICE

WILLIAM LENOX, OF RUSSELL, NEW YORK

BEDSTEAD

Application filed December 30, 1927. Serial No. 243,674.

This invention has reference to bedsteads, and aims to provide a bedstead of the foldable type whereby the bedstead may be folded against the wall to facilitate cleaning and 5 may be moved from room to room without the necessity of disconnecting the head and foot portions of the bed.

Another object of the invention is to provide a bedstead so constructed that it will 10 stand when folded, to the end that the bedstead may be readily and easily moved on its casters.

With the foregoing and other objects in view which will appear as the description proceeds, the invention resides in the combination and arrangement of parts and in the details of construction hereinafter described and claimed, it being understood that changes 15 in the precise embodiment of the invention herein disclosed, may be made within the scope of what is claimed, without departing from the spirit of the invention.

Referring to the drawings:

Figure 1 is a plan view of a bedstead constructed in accordance with the invention.

Figure 2 is a side elevational view thereof.

Figure 3 is a plan view of the bed in its folded condition.

Figure 4 is a sectional view taken on line 30 4—4 of Figure 2.

Figure 5 is a detail view partly in section of one of the end posts to which the side rails are connected.

Referring to the drawings in detail, the bed 35 includes a head 5, foot 6 which are connected by the side rails 7.

The head section and foot section each includes vertical corner posts 8 connected by means of the transversely disposed members 40 9, which in turn are connected by means of the vertical members 10 supplied with balls 11 at their ends for ornamental purposes.

The head and foot sections also embody 45 inwardly extended members 12 connected with the corner posts at points adjacent to

the lower ends thereof, the inner ends of the members 12 being supplied with T-joints 13 through which the rods 14 extend, which rods also extend through the T-joints 15 secured at the ends of the spaced side rails 7 of the 50 bed.

At the lower ends of the rods 14 are winged nuts 17 that may be operated to set up a binding action between the T-joints 13 and 55 15 to hold the side rails against pivotal movement with respect to the head section and foot section of the bed.

The posts being hollow, permit suitable electric wires to be extended therethrough and connected with the lamp 18 so that a reading lamp is provided for the persons occupying the bedstead.

The inwardly extended members 12 are arranged in pairs, the lower members 12 at each end of the bedstead being connected by 60 means of the horizontal members 19 to further brace the head and foot sections of the bed and hold the bed rigid as it is being moved from place to place, it being understood that the construction of the head and foot section 65 is such as to hold the bedstead in an upright position when it is being rolled on its casters from place to place.

The side rails 7 are connected at points intermediate their ends by means of vertical 70 members 20, which hold the side rails 16 in proper spaced relation with each other at all times.

The casters 21 are supported in the lower ends of the corner posts of the bedstead in 80 the usual and well known manner.

I claim:

A folding bedstead including a head section and a foot section, spaced inwardly extended members on the head and foot sections, T couplings at the free ends of the inwardly extended members, side members formed of spaced horizontal bars having T couplings at their ends, the T couplings of the side sections being disposed in alignment 85 90

and in contact with the couplings of the inwardly extended members, rods extending through the T couplings to pivotally connect the side members, and means on the rods for setting up a binding action between the T couplings to hold the side members against movement.

In testimony that I claim the foregoing as my own, I have hereto affixed my signature.

WILLIAM LENOX.
